UNITED STATES PATENT OFFICE.

ADOLPH S. ELLISON, OF NEW YORK, N. Y.

DESIGN FOR COLLARETTE.

Specification forming part of Design No. 6,988, dated November 11, 1873; application filed October 30, 1873.
[Term of Patent 3½ years.]

To all whom it may concern:

Be it known that I, ADOLPH S. ELLISON, of the city, county, and State of New York, have invented a new and original Design for Collarette; and I do hereby declare the following to be a full, clear, and exact description thereof, which will enable those skilled in the art to make and use the same, reference being had to the accompanying drawing forming a part of this specification, in which drawing—

Figure 1 represents a side view of my design. Fig. 2 is a transverse section of the same.

Similar letters indicate corresponding parts.

This invention relates to the design for a collarette, which is ornamented by a set of loops made of chenille, or other suitable material, which are connected to each other and to the collarette by an ornamental border, the whole being so arranged that an article is obtained of a distinguishing and ornamental appearance.

In the drawing, the letter A designates a

collarette, made of lace or other suitable material, in the ordinary form or shape. With this collarette I have combined a set of loops, a, by preference made of chenille of any desired color. These loops are connected to each other and to the collarette A by an ornamental border, b. The effect is still further improved by an additional set of loops, c, which are somewhat smaller than the loops a, and which alternate with the same. By these means a collarette is produced which has a novel and distinguishing appearance.

What I claim as new, and desire to secure by Letters Patent, is—

The design for a collarette, as shown and described.

This specification signed by me this 24th day of October, 1873.

A. S. ELLISON.
